UNITED STATES PATENT OFFICE

GILLES HOLST, OF EINDHOVEN, NETHERLANDS, ASSIGNOR TO N. V. PHILIPS' GLOEILAMPENFABRIEKEN, OF EINDHOVEN

ELECTRON DISCHARGE TUBE

Application filed October 28, 1924, Serial No. 746,396, and in Germany November 27, 1923.

This invention has reference to an improved discharge tube comprising an incandescent cathode, an anode and a controlling grid and has for its object the use of a cathode consisting of material that, at a temperature materially lower than is necessary for a cathode made of tungsten, emits a sufficient quantity of electrons for operating the tube, in combination with one or more auxiliary electrodes provided in the tube in addition to the controlling grid.

Many materials may be used for constituting at least part of the surface of the cathode in order to allow the latter to emit at an approximately low temperature a number of electrons sufficient for the operation of the tube. As suitable materials, for example, thorium or a compound of thorium has been mentioned, which at a temperature of about 1300-1380° K. emits a number of electrons equal to that emitted by tungsten towards 2000° K. It has also been suggested to coat the surface of the cathode with compounds of earth alkalies and more especially with their oxides.

It is known, moreover, to provide the discharge tube with one or more grids in addition to the controlling grid. Such a grid may, for example, be arranged near the cathode in order to suppress the space charge, or near the anode in order to serve as an anode-screen. The use of the said grids and more especially of the space-charge grid allows a material reduction in the anode tension of a three-electrode tube, in comparison with the tension of a tube without a space charge grid, if the two tubes are otherwise in the same condition.

The invention has the advantage that the tensions which have to be supplied to the anode and to the incandescent cathode and the consumption of energy can be reduced materially in comparison with the tensions and the consumption of energy of a three-electrode tube provided with a cathode made of tungsten. The total energy required for operating the tube, for example, as an amplifier in wireless telegraphy may be supplied by five or six dry cells.

In practice it has been found that a

cathode adapted to be operated at a low temperature renders the characteristic curve of the tube less inclined than a cathode made of tungsten and having the same current of saturation. The present invention obviates this disadvantage because especially a space-charge grid makes the curve again more inclined.

The accompanying drawings illustrate, by way of example some embodiments of the invention.

Figure 1 is an elevation partly in section of a tube provided with a space-charge grid.

Figure 2 shows the electrodes and the leading-in wires of a tube comprising an anode-screen with their supports.

Figure 3 illustrates a construction of a tube comprising a space-charge grid and an anode-screen.

The drawings show the exhausted glass envelope 1 of a tube comprising a glass stem 2, the leading-in wires and the supports being sealed in the latter in the usual manner. The anode is indicated in the figures by the reference numeral 3 and a helical controlling grid by the reference numeral 4. In the constructions illustrated the two cylindrical electrodes 3 and 4 are arranged concentrically around the straight cathode 5 as their axis. The said cathode consists entirely or partly of material yielding at the same temperature a considerably greater emission of electrons than tungsten. For example, part of the surface of such a cathode may be covered with oxides of earth alkalies.

The Figures 1 and 3 show, in addition to the said electrodes, a helical space-charge grid 6, arranged near the cathode and serving to suppress substantially the space charge which impedes the emission of the electrons in the vicinity of the cathode.

The Figures 2 and 3 show constructions comprising a helical anode-screen 7, arranged near the anode in order to impart a greater inclination to the characteristic curve of the tube in the most favourable operating range.

The said grids may be secured in any suitable manner, for example, by sealing each turn of the grid to a supporting rod 11.

The tube is provided with a base having a metallic cap 8, having arranged in it a contact screw 9 to which one of the leading-in wires is connected. The other leading-in wires are connected by means of conductors to the plugs 10 which may be arranged in an insulating plate of the cap.

The low consumption of energy for such a tube permits locating the cells required for the operation of the tube in the little case that ordinarily contains the other devices belonging to a wireless installation.

What I claim is:

A discharge tube comprising a glass envelope, a base to which the envelope is sealed, a press supported by said base, a straight filamentary cathode perpendicular to the direction of the press, a cylindrical control grid mounted about the filament as axis, a cylindrical plate concentric with the control grid, an auxiliary cylindrical grid between the filament and the control grid, a second auxiliary cylindrical grid mounted between the control grid and the anode, prongs projecting downwardly from said base, an additional terminal on the base, a lead from one of the electrodes to said terminal, and leads from the remaining electrodes to the prongs.

In testimony whereof I affix my signature,
at the city of Eindhoven, this 22nd day of
September, 1924.

GILLES HOLST.
